ROTARY PUMP WITH FLUID CONTAINER
FOR LAVATORY

Hal C. Brannam, Tulsa, Okla.

Application May 7, 1947, Serial No. 746,425

2 Claims. (Cl. 4—159)

1

This invention relates to a rotary pump, and more particularly but not by way of limitation to a rotary pump adapted for use in beauty parlors, barber shops, and the like.

In present day beauty parlors in applying a permanent wave by the cold wave method, the usual procedure of neutralizing the cold wave; that is, the hardening of the customer's hair after it has been previously softened by a suitable lotion for conforming the hair to the shape of the curlers, it is necessary that the operator apply the neutralizing lotion to the hair while it is wrapped around the curlers. This application is done by continuously dipping from a container containing the lotion and pouring it on to the hair wrapped around the curler. It will be apparent that this is a laborious and unsatisfactory procedure. Furthermore, this operation is disliked by beauty parlor operators, and as a consequence the operation is usually very inefficient, which usually results in a very unsatisfactory permanent wave to the customer. The operation is normally done while the customer is reclining with the nape of the neck resting on a shampoo board, or the like, thereby making it very difficult to apply the neutralizing lotion to the hair wrapped in curlers near the nape of the neck. This often provides a straight hair result in lieu of a permanent wave or curl as is desired. Furthermore, pouring or dipping of the neutralizing lotion will not provide for complete penetration to the ends of the hair in the curlers, again resulting in a straight end result.

The present invention is more generally concerned with a rotary basin pump which may be conveniently disposed in a lavatory or basin for utilizing the water pressure of the lavatory spigot as a hydraulic power medium. The basin of the pump is filled with neutralizing lotion capable of being force pumped for spraying onto the customer's hair in order to eliminate the old and inefficient method of dipping or pouring set out above.

It is an important object of this invention to provide a rotary pump adapted for use in beauty parlors, or the like, where various hair dressing solutions may be sprayed onto the customer's hair in a convenient and efficient manner.

And still another object of this invention is to provide a rotary pump adapted to cooperate with the water spigot of a conventional lavatory wherein fluid to be pumped is contained in a vessel in such a manner to be sprayed from the vessel by the pump.

And still another object of this invention is to provide a basin type pump for use in beauty parlors, or the like, adapted to be disposed in a lavatory and connected to the water spigot thereto wherein the water pressure activates the pump to force fluid in the basin therefrom in order to be sprayed.

2

Other objects and advantages of the invention will be evident from the following detailed description read in conjunction with the accompanying drawings which illustrate my invention.

In the drawings:

Figure 1 is a perspective view showing the disposition of the pump in the lavatory.

Figure 2 is a sectional elevational view of the invention showing the pump disposed in the lavatory.

Figure 3 is a detail view in sectional elevation of the operating parts of the pump on line 3—3 of Figure 4.

Figure 4 is a view taken on lines 4—4 of Figure 3.

Referring to the drawings in detail, reference character 2 indicates a conventional lavatory provided with the usual water spigots 4. The present invention comprises a bowl-like body 6 forming a container. The container 6 is adapted to be connected with a pump housing 8 secured to the substantially flat face or boss 9 of the lowermost portion of the container 6 through a plurality of circumferentially spaced screws 10

(preferably four in number) threaded into the circumferentially spaced apertures 12 of the housing 8, as clearly shown in Figure 3. The housing is an irregular shaped body in plan, as clearly shown in Figure 4. However it is substantially circular throughout, with the exception of the diametrically opposed outwardly extending flange portions 14 and 16, for a purpose as will be hereinafter set forth. The flanges 14 and 16 are provided with downward extending legs 18 and 20 while the remaining portion of the housing 8 at a point substantially perpendicular to the legs 18 and 20 is provided with outwardly and downwardly extending leg members 21 and 22. It will be apparent that the leg members permit disposition of the assembled pump indicated generally by 24 in the recess 26 of the lavatory 2, as clearly shown in Figure 2. Furthermore, the leg portions of the housing 8 support the pump at a point away from the bottom of the recess 26 for a purpose as will be hereinafter set forth.

The flange portion 14 is provided with an aperture or passageway 28 connecting with a tubular member 30 secured to the flange 14. Similarly, the flange 16 is provided with an aperture 32 connecting with a tubular member 34 secured thereto. The upper portion of the housing 8 is provided with a cylindrical cavity or chamber 36 in communication with the passageway 32. A similar cavity or chamber 38 is provided in the lower portion of the housing 8, separated from the chamber 36 by the baffle member 40, as clearly shown in Figure 3. The chamber 38 connects with the passageway 28 as shown in Figures 3 and 4. The baffle 40 is provided with an aperture 42 for receiving a stud

50

55

60

shaft 44 extending thereunto and into the chambers 36 and 38. An apertured boss 46 is provided on the upper portion of the baffle 40 while a similar apertured boss 48 is provided on the lower side of the baffle 40, for a purpose as will be hereinafter set forth. An impeller or wheel 50 is disposed in the chamber 36 and comprises a central apertured body portion 52 having a plurality of peripherally spaced outwardly extending blades 54 thereon. The lower face of the body 52 is provided with a recess 56 in substantial conformity with the boss 46 to assure proper disposition of the impeller wheel 50 in the chamber 36. A similar wheel 58 is disposed in the chamber 38 and comprises a central apertured body portion 60 having a plurality of peripheral teeth or blades 62. It is to be noted that the blades 62 are slightly shorter in length than the blades 54 for the impeller wheel 50. This will be apparent from an inspection of Figures 2 and 3. The impeller wheels 50 and 58 are maintained in the chambers 36 and 38 by the nuts 64 and 66 secured to the opposite ends of the stud 44.

The tubular members 30 and 34 provide a connection for receiving the usual rubber hose 70 and 72. The hose 70 is connected at one end with spigot 4 to provide a connection with the chamber 38. Hose 72 is connected with the cylinder 34 and at the opposite end is provided with a spray element 74 for a purpose that will be hereinafter set forth. The cavity 76 of the container 6 is provided with an aperture 78 in its extreme lowermost portion thereof in order to provide communication between the chamber 76 and the chamber 36.

Operation

The operation of the pump will be apparent from the above, in that it is placed in the basin 26 of the lavatory 2 with the conduit 70 connected to the water spigot 4. Any suitable neutralizing solution or the like is poured into the bowl 76 of the container 6. The valve stem 78 of the spigot is moved to open position thereby creating a water pressure from the spigot 4 into the chamber 38 and into contact with the plurality of peripheral blades 62 of the impeller 58. This will cause a rotation of the impeller 58 and through the medium of the stud 44 will provide a simultaneous rotation of the impeller 50 disposed in the upper chamber 36. The aperture 78 provides communication of the neutralizing fluid in the chamber 76 with the chamber 36, whereby rotation of the impeller 50 will force the neutralizing fluid directed into cavity 36 out the aperture 32, hose 72 and spray element 74.

It will thus be seen that the pump utilizes the water pressure of a conventional lavatory as an actuating medium for pumping or forcing a fluid from the container 6 through the rubber conduit 12 where it is sprayed from element 74. This spraying provides a very efficient and convenient means of applying a fluid to a customer's hair in various beauty parlor operations. The spraying assures that an overall and efficient application of the fluid will be made to all parts necessary. Furthermore, the spraying operation eliminates considerable time in applying a neutralizing solution or the like in beauty parlor operations, and also tends to eliminate any inefficiency of operators which may result in unsatisfactory waves.

It will be apparent that the pump is not limited to the application of a neutralizing solution for 75

cold waves, but can be used in numerous other beauty parlor or barber shop operations, such as special rinses during the shampooing of the hair, or the application of color rinses after a shampoo. The present method of applying color rinses is usually by pouring or brushing the color rinse through the hair. The present invention would obviously provide better results since the color rinse could be sprayed on and thereby apply the rinse with a more even force.

From the foregoing it will be apparent that the present invention provides a new and novel means for creating a spray application in a liquid pump, particularly adaptable to beauty parlor and barber shop operations in order to secure a more efficient and convenient application of liquids for various operations on the hair. Furthermore, the present device for spraying the hair solution to the customer creates a force to assure application of the solution to all desired parts; at the same time rendering the application in an expeditious and economical manner.

Changes may be made in the combination and arrangements of parts as heretofore set forth in the specification and shown in the drawings, it being understood that any modification in the precise embodiment of the invention may be made within the scope of the following claims without departing from the spirit of the invention.

What I claim is:

1. In combination with a lavatory, a fluid container freely disposed therein, a pump housing secured to the bottom portion of the container and communicating therewith, a plurality of separated baffled chambers in the housing, a rotary impeller in each of the chambers, a shaft connecting the impellers to provide simultaneous rotation thereof, a conduit connecting one of said chambers with the lavatory spigot to provide a hydraulic pressure causing rotation of the impeller disposed therein, said impeller rotation causing a simultaneous rotation of the other of said impellers in the other of said chambers providing a displacement of fluid from the communicating container, and spray means providing a discharge of the displaced fluid.

2. In combination with a lavatory, a fluid container disposed therein, a pumping apparatus secured to the container, means connecting the pumping apparatus with the lavatory spigot to provide hydraulic power therefor, a pair of separated impeller means provided in the pump, means connecting the impellers to provide simultaneous rotation thereof, one of the said impellers responsive to the force of the hydraulic power to cause rotation of both impellers, and the other of said impellers providing for displacement of fluid in the container, and means providing a spray outlet for the displaced fluid.
